UNITED STATES PATENT OFFICE.

ALFRED P. FINGER, OF JACOBS FORK, NORTH CAROLINA.

SHINGLE-MACHINE.

SPECIFICATION forming part of Letters Patent No. 752,055, dated February 16, 1904.

Application filed February 24, 1902. Serial No. 95,573. (No model.)

To all whom it may concern:

Be it known that I, ALFRED P. FINGER, a citizen of the United States, residing at Jacobs Fork, in the county of Catawba and State of North Carolina, have invented a new and useful Shingle-Machine, of which the following is a specification.

The invention relates to improvements in shingle-sawing machines.

The object of the present invention is to improve the construction of shingle-sawing machines and to provide a simple and comparatively inexpensive one which will be adapted to cut rapidly shingles of a uniform thickness and in which the carriage will be securely held against lateral movement.

A further object of the invention is to provide a shingle-sawing machine of this character adapted to be used in connection with any ordinary saw for cutting slats or ripping lumber and capable of automatically shifting a shingle-block as it is advanced or fed forward, whereby the shingles will be cut from the block with their thick ends alternately at opposite ends of the same.

A further object of the invention is to enable the shingle-block to be held without liability of losing or wasting any of the material.

The invention consists in the construction and novel combination and arrangement of parts hereinafter fully described, illustrated in the accompanying drawings, and pointed out in the claims hereto appended.

In the drawings, Figure 1 is a perspective view of a shingle-sawing machine constructed in accordance with this invention. Fig. 2 is a vertical sectional view taken longitudinally of the carriage. Fig. 3 is a detail sectional view illustrating the construction for locking the laterally-movable shingle-block-carrying frame against forward movement when the oscillatory actuating device is elevated. Fig. 4 is a similar view illustrating the construction of the slides and showing the arrangement of the spring for actuating the laterally-movable shingle-block-carrying frame to set the same in a plane parallel with the rails preparatory to applying a shingle-block to it.

Like numerals of reference designate corre-

sponding parts in all the figures of the drawings.

1 1 designate a pair of rails connected by a suitable cross-tie 2 and having oppositely-beveled upper faces, forming an apex and presenting inclined inner side faces 3, to which is secured bars or strips 4, which project outward and upward beyond the apexes of the tracks and which are arranged to be engaged by hooks 5 of slides 6 of a carriage 7. The slides, which are thus interlocked with the rails, consist of transverse metal plates secured to the bottom of the carriage 7. By interlocking the carriage and the rails in this manner the former is securely held against transverse movement, and a uniform thickness of shingle is thereby insured. The sawmill-carriage, which moves longitudinally of the rails to carry a shingle-block against a saw, is provided with longitudinal beams 8 and 9, and it has transverse bars 10 and 11, secured to the beams 8 and 9 at the ends thereof and provided at their upper faces with metal bars or plates 12, having inwardly-projecting longitudinal edges, forming flanges and providing ways for slides 13 of a laterally-movable shingle-block-carrying frame 14. The guide-bars 10 and 11 are suitably secured to the longitudinal beams 8 and 9, and a handle bar 15 is secured to one of the guide-bars 11 by means of brackets 16. The brackets 16, which are arranged at the ends of the transverse handle-bar 15, are approximately U-shaped, being composed of two sides and a transverse connecting portion. The sides are secured at their lower ends to the said guide-bar 11, and the transverse connecting portion is curved to conform to the configuration of the handle-bar.

Each slide 13 consists of a horizontal bar located at the bottom of the laterally-movable shingle-block-carrying frame and provided with an arm 17, extending upward from one end of the bar and rigidly secured to the frame 14. The arm is provided with opposite notches 18 to receive the inwardly-projecting flanges of the guide-bars 10 and 11, the slide-bar being located beneath the flanges, whereby the laterally-movable shingle-block-carrying frame is unlocked with the sawmill-

carriage. Each slide is supported by braces 21 and 22, which are secured at their upper ends to the upper edge of the head-block. The brace 21 extends longitudinally of the slide, and its lower end is riveted or otherwise secured to the bottom slide-bar 13.

The brace 22, which diverges upwardly from the brace 21, is provided at its lower end with a slot 24 to receive the fastening device 25 to 10 secure the braces together. The slot permits a limited movement of the braces on each other at their point of connection to permit the head-block of the laterally-movable frame to have the necessary play to enable it to be 15 arranged at an angle to the plane of the rails to set the shingle-block in proper position for a shingle.

The slide 13 is subjected to torsional strain at the point of its connection with the arm 17 20 and serves to assist in returning the frame to a central position after the latter has been released from the position to which it is adjusted during the sawing operation.

The laterally-movable shingle-block-carrying frame consists of the head-block or body portion 20, which rests upon the guide-bars of the sawmill-carriage frame and has connected to it, at the bottom thereof, by hinges 26 a hinged oscillatory actuating and locking 25 device 27, consisting of a bar or body portion provided with an arm 28, extending rearward from the center of the body and supporting one end of a handle 29. The handle 29 is supported by brackets 30 and 31, constructed 30 similar to the handle-supporting brackets 16 and composed of sides and connecting transverse portions, which are curved to conform to the configuration of the handle, which is round.

40 Mounted on the oscillating actuating device at the ends of the body portion is a pair of pawls 32 and 33, pivoted at their upper ends and curved downward and rearward, as clearly shown in Fig. 1, and provided at their lower 45 ends with engaging portions, which are adapted to engage teeth of ratchet-bars 34 and 35. The ratchet-bars 34 and 35 are each provided with teeth 36 and 37 of unequal length arranged at regular intervals, the teeth at one 50 side of the laterally-movable frame being staggered with relation to the teeth at the opposite side or arranged between the intervals. The teeth at one side being located opposite the intervals and out of alignment with the 55 teeth of the opposite side are adapted to hold one of the pawls in advance or in rear of the other, whereby when the actuating device is swung downward to advance the laterally-movable frame and to force the pawls against 60 the teeth the engaging end of one of the pawls will be in advance of the other and the head-block of the laterally-movable frame will be set at an angle to the plane of the saw, and thereby held in proper position for cutting a shingle. The pawls may be spring-

actuated or gravity-acting, and when the hinged actuating device is swung upward the pawls are thereby carried forward on the ratchet-bars, one of the pawls being carried to a position slightly in advance of one of the 70 long teeth of the adjacent ratchet-bar, and the other pawl being carried to a position slightly in rear of the engaging face of the corresponding large tooth of the other ratchet, whereby when the actuating device is swung 75 downward one pawl will engage the large tooth of one ratchet-bar and the other pawl will be carried rearward slightly and into engagement with one of the small teeth of the adjacent ratchet-bar. The head-block or body 80 of the laterally-movable shingle-block-carrying frame will be firmly locked at an angle to the plane of the saw. When the hinged actuating device is swung upward, the rear pawl or dog will be carried in advance of the large 85 tooth of the adjacent ratchet-bar, and when the actuating device is swung downward the position of the head-block or body of the shingle-carrying frame will be reversed. The ratchet-bars are suitably secured to the inner 90 guide-bars 10 and are offset therefrom, the ends of the ratchet-bars being preferably bent at an angle to form attaching portions or arms. The ratchet-bars are connected at intervals between their ends with the guide-bars 95 10 by suitable fastening devices, preferably consisting of bolts 38. The engaging ends of the pawls are recessed slightly to enable them to straddle the ratchet-bars to prevent lateral disengagement of the pawls or dogs.

In order to lock the laterally-movable shingle-block-carrying frame against forward movement to prevent any shifting of the same, the actuating device is provided at the outer or rear end of its arm with a depending 105 pin 39, which is located above a series of staggered socket-openings 40 of a bar or plate 41, and these sockets are located alternately at opposite sides of the center and are arranged to receive the pin of the arm which 110 co-operates with the locking dogs or pawls to hold the laterally-movable shingle-block-carrying frame rigid with the sawmill-carriage during the sawing operation. The plate or 115 bar 41 is secured to a pair of parallel supporting-bars 42, having enlarged intermediate portions 43, which form shoulders for engaging the inner faces or edges of the side beams of the sawmill-carriage, and they are secured to the same by means of pivoted latches 43^a. 120 The pivoted latches 43^a, which are approximately U-shaped, are suspended from the inner faces of the bars 42 and engage pins or projections 44 of the side beams of the sawmill-carriage. By this construction the transverse bar or member 41 is detachably secured to the sawmill-carriage. The pin of the arm of the actuating device extends downward into the space between the bars 42; but the transverse bar or member 41 may be provided with 125 130

any other form of apertures or sockets for the reception of the pin.

When the actuating device is swung upward to carry the pawls or dogs forward over the ratchet-bars, the laterally-movable shingle-block-carrying frame is held against accidental forward movement by means of a resilient locking-dog 45, mounted on the front portion of the actuating device and extending through a curved slot 46 of the head-block and located above and arranged to engage a ratchet of the plate or member 41. The ratchet 47 consists of a series of shouldered teeth formed by recessing the bar or member 41 at one side thereof; but any other form of ratchet may be employed. The locking device 45 is resilient to enable it to yieldingly engage the ratchet, and it is adapted to prevent the laterally-movable frame from advancing when the actuating device is swung upward. When the actuating device is swung downward, the resilient locking device or dog 45 is lifted out of the ratchet and the shingle-block-carrying frame is permitted to advance, as before described.

The pawls or dogs 32 and 33 are positively clamped in engagement with the ratchet-bars by means of locking-arms 48, fixed to the body portion of the actuating device adjacent to the ends thereof and provided with laterally-extending portions located above and adapted to engage the pawls or dogs 32 and 33 at the upper faces thereof. These locking-arms will prevent the pawls or dogs from being accidentally thrown out of engagement with the ratchet-bars by any vibration or jar of the machine.

When it is desired to move the shingle-block-carrying frame rearward to apply a block to the same, the pawls or dogs 32 and 33 are locked in an elevated position by means of a pair of reciprocating rods 49 and 50, mounted in suitable guides 51 of the actuating device and connected at their inner ends with an operating-lever 52 and adapted to be projected outward beneath the pawls or dogs 32 and 33 when the actuating device is depressed and in engagement with the transverse bar or member 41. When the reciprocating rods are thus engaged with the pawls or dogs, the actuating device when swung upward will carry the said pawls or dogs out of engagement with the ratchet-bars. The lever 52, which is pivoted between its ends, is provided at its upper end with a suitable handle, and the inner ends of the locking-rods are connected with the lever 52, at opposite sides of the fulcrum thereof. The lever 52, which is arranged in an upright position, is preferably pivoted to the body portion of the actuating device, at one side of the arm thereof, and the rod 50 is angularly bent to clear the said arm.

The shingle-block is secured to the head-block of the laterally-movable shingle-block-carrying frame by means of fixed clamps 53

and 54 and a movable clamp. The fixed clamps 53 and 54 consist of plates secured to the head-block, at the bottom thereof and at a point adjacent to the top of one end of the same, and these plates have offset engaging portions or jaws provided with teeth and adapted to be embedded in the shingle-block without injuring the same. The adjustable clamp consists of a pair of upright guide plates or bars 55, located at opposite sides of a recess of the head-block and terminating at their lower ends in jaws 56, and a movable slide 57, arranged between the guide plates or bars and provided with an upper clamping-jaw 58. The vertical guide plates or bars 55 form a way, and the stationary jaws 56 are arranged at the bottom thereof. The slide consists of a vertical plate arranged in the way and provided with a block or piece 60, arranged between the guide plates or bars 55 and fixed to or formed integral with the plate or body portion of the slide. The upper jaw, which engages the top of the block, consists of a plate or piece centrally connected with the slide and having outwardly-offset side portions arranged to clear the guide plates or bars and provided with depending engaging portions or teeth, which are adapted to be embedded in the upper face of the shingle-block. The slide is connected by a link 61 with an operating-lever 62, fulcrumed at one end on the head-block and connected between its ends with the said link and adapted to be readily operated to force the movable jaw of the clamp into the shingle-block. By this construction the shingle-block is securely clamped to the head-block or body portion of the laterally-movable shingle-block-carrying frame without wasting or spoiling any of the material.

When a shingle-block has been secured to the head-block or body portion of the laterally-movable frame, the same is advanced by oscillating the actuating device, which feeds the head-block forward by a step-by-step movement, which alternately arranges the shingle-block with its inner face at an angle to the plane of the saw, and the said shingle-block is changed from one position to the other, so that the shingles will be cut with their enlarged ends alternately at opposite ends of the block. The forward movement of the shingle-block-carrying frame is limited by projections or pins 63 and stops 64 to prevent the said frame from coming in contact with the saw. The pins or projections 63 depend from the head-block and are arranged between the transverse guide-blocks of the sawmill-carriage, and the stops consist, preferably, of transverse pins or fastening devices, which extend across the spaces between the guide-bars 10 and 11. After the actuating device is operated to arrange the block in position for sawing a shingle the carriage is moved longitudinally of the rails to carry the shingle-block against the saw. The handle of

the actuating device and the handle of the carriage are arranged in convenient position to enable them to be simultaneously grasped by the operator.

5. What I claim is—

1. In a machine of the class described, the combination with a carriage having transversely-disposed and spaced guide-bars, of a transversely-movable shingle-block-carrying frame, slides secured to said frame and adapted to the guide-bars, said slides being yieldable to permit angular adjustment of the frame and serving to assist in returning the frame to a central position when said frame is released.
2. In a machine of the class described, the combination of a carriage provided at opposite sides with ratchet-bars, a laterally-movable frame mounted on the carriage and provided with pawls engaging the ratchet-bars, means for simultaneously operating the pawls for successively advancing the same into engagement with the ratchet-teeth in advance of the movement of the frame, the teeth of the ratchet-bars being so disposed as to cause the frame to alternately assume positions at opposite angles with respect to the carriage, and means for locking the frame in either position, substantially as specified.
3. In a machine of the class described, the combination of a carriage provided at opposite sides with ratchet-bars provided with teeth, the teeth of one ratchet-bar being disposed opposite the intervals between the teeth of the other ratchet-bar, a laterally-movable frame mounted on the carriage, pawls or dogs carried by the frame and engaging the ratchet-bars, means for operating said pawls or dogs to move the same into engagement with successive teeth in advance of the movement of the frame and for subsequently advancing the frame and set the same at an angle to the direction of movement of the carriage, means for operating the pawls or dogs, and a locking device for holding the frame rigid with the carriage in either position, substantially as described.
4. In a machine of the class described, the combination of a carriage provided with opposite ratchet-bars, a laterally-movable frame mounted on the carriage and capable of horizontal movement for setting it at an angle to the direction of movement of the carriage, an oscillatory actuating device provided with pawls or dogs arranged to engage successive teeth of the ratchet-bars in advance of the movement of the frame and for subsequently advancing the frame, and means mounted on the actuating device for engaging the carriage to lock the frame rigid with the carriage, substantially as described.
5. In a machine of the class described, the combination of a carriage provided with opposite ratchet-bars, a laterally-movable frame

65 mounted on the carriage, an oscillatory actuating device hinged to the frame and provided with pawls or dogs for engaging the ratchet-bars, a locking device carried by the oscillatory actuating device, and a bar or member mounted on the carriage and provided with 70 staggered sockets for the reception of the locking device, substantially as described.

6. In a machine of the class described, the combination of a carriage, a laterally-movable shingle-block-carrying frame capable of horizontal movement for setting it at an angle to the direction of movement of the carriage, and an oscillatory actuating device provided with 75 means for engaging the carriage for advancing the frame and coöperative means on the carriage for alternately setting the frame at opposite angles to the direction of movement of the carriage, said actuating device being also provided with means for locking the frame rigid with the carriage, the frame-advancing 80 and frame-locking means being successively operated by the movement of said actuating device, substantially as described.

7. In a machine of the class described, the combination of a carriage provided with 90 opposite ratchet-bars, a laterally-movable shingle-block-carrying frame, a vertically-movable oscillatory actuating device mounted on the said frame and provided with means for engaging the ratchet-bars and having a locking pin 95 or projection, and a bar or member mounted on the carriage and located beneath the oscillatory actuating device and provided with staggered apertures, substantially as described.

8. In a machine of the class described, the 100 combination of a carriage, a laterally-movable shingle-block-carrying frame mounted on the carriage, a movable actuating device mounted on the frame and provided with means for engaging the carriage for advancing the frame 105 and coöperative means on the carriage for setting the same at an angle, said actuating device being provided with opposite locking devices, one of the locking devices being arranged to hold the frame rigid with the carriage and the other locking device being arranged to limit the forward movement of the frame and being adapted to lock the same against forward movement, the frame-advancing 110 and frame-locking means being successively operated by the movement of said actuating device, substantially as and for the purpose described.

9. In a machine of the class described, the 120 combination of a carriage, a laterally-movable frame, ratchet-bars mounted on the carriage, a bar or member having staggered apertures or sockets and having a ratchet, an oscillatory actuating device mounted on the frame and provided with a locking pin or projection for 125 engaging the apertures or sockets, oppositely-disposed pawls mounted on the actuating device and arranged to engage the ratchet-bars

for advancing the frame, and a reversely-arranged pawl or dog mounted on the actuating device and arranged to engage the ratchet of the said bar or member, substantially as described.

10. In a machine of the class described, the combination of a carriage having ratchet-bars, a shingle-block-carrying frame, an oscillatory actuating device provided with means for engaging the teeth of the ratchet-bars for feeding the frame forward and for setting the same at an angle, a locking device carried by the actuating device for holding the frame rigid with the carriage, and a pawl or dog carried by the actuating device and arranged to lock the frame against forward movement when the actuating device is swung backward or outward for setting or arranging the parts for feeding the frame forward, substantially as described.

11. In a machine of the class described, the combination of a carriage, a laterally-movable shingle-block-carrying frame, ratchet-bars located at opposite sides of the carriage, a hinged actuating device provided with pivoted dogs engaging the ratchet-bars, and arms fixed to the hinged device and arranged to engage the pawls for locking the same in engagement with the ratchet-bars, substantially as described.

12. In a machine of the class described, the combination of a carriage, a laterally-movable shingle-block-carrying frame, ratchet-bars mounted on the carriage, pivoted pawls for engaging the ratchet-bars, an oscillatory actuating device carrying the pivoted pawls, reciprocating locking-bars mounted on the actuating device and arranged to engage the

pawls, and a lever connected with the rods for operating the same, substantially as described.

13. In a machine of the class described, the combination of a carriage provided with opposite ratchet-bars, an intermediate bar or member having a ratchet and provided with staggered apertures or sockets, a hinged actuating device provided with an arm having a locking-pin for engaging the apertures or sockets, pivoted pawls mounted on the actuating device and engaging the ratchet-bars, rigid arms located above the pawls and carried by the said actuating device for locking the pawls in engagement with the ratchet-bars, means for engaging the pawls to hold the same out of engagement with the ratchet-bars when the actuating device is swung upward, and a resilient dog extending forward from the actuating device and engaging the ratchet of the bar or member when the actuating device is swung upward, substantially as described.

14. In a machine of the class described, the combination with a shingle-block-carrying frame, of a pair of spaced guide bars or plates mounted on the frame and provided at their lower ends with fixed dogs for engaging a shingle-block, a slide adapted to said guide-plates, a movable jaw secured to said slide and projecting beyond the outer faces of the guide-plates, and an operating-lever connected to said slide.
